United States Patent

Des. 239,378

Patented Mar. 30, 1976

239,378

VEHICLE STEP

Alvin Stecker, Sr., Woden, Iowa 50484

Filed Jan. 23, 1975, Ser. No. 544,937

Term of patent 14 years

Int. Cl. D12—16

U.S. Cl. D12—203

FIG. 1 is a perspective view of a vehicle step showing my new design in association with a vehicle which has been shown fragmentarily in broken lines for illustrative purposes only;

FIG. 2 is an enlarged perspective view thereof;

FIG. 3 is an enlarged top plan view thereof;

FIG. 4 is an enlarged side elevation view thereof;

FIG. 5 is an enlarged front elevation view thereof;

FIG. 6 is an enlarged rear elevation view thereof; and

FIG. 7 is an enlarged bottom plan view thereof.

I claim:

The ornamental design for a vehicle step, substantially as shown and described.
